ATTYS.

UNITED STATES PATENT OFFICE.

ERNEST G. BEVERIDGE, OF BROOKLYN, NEW YORK, ASSIGNOR, BY MESNE ASSIGNMENTS, TO R. HOE AND CO., INC., OF NEW YORK, N. Y., A CORPORATION OF NEW YORK.

WRINKLE REMOVER FOR WEB ROLLS.

Application filed September 6, 1922. Serial No. 586,419.

This invention relates to certain improvements in devices for smoothing out or removing wrinkles in webs as the web comes from the web roll, and has been designed particularly for use in smoothing out the webs used in printing machines.

These webs, as ordinarily supplied to the printer, are wound on cores and are of varying widths, some of the rolls being very wide, particularly those adapted for printing in double-wide presses. In the winding of the webs into the roll form, there is a tendency for the webs to wind more tightly at the edges than in the center of the roll with the result that wrinkles are formed in the webs, particularly at the outer edges thereof. In high class printing, either black or color, it is very desirable that the web should pass between the printing members with a smooth surface and without these wrinkles, because if these wrinkles be present, an impression results which is very disadvantageous in the printing, particularly in the fine printing produced in intaglio or rotogravure machines.

It is the especial object of the invention to produce a device by which the unevenness in the web caused by wrinkles, is eliminated so that the web goes to the printing couple with a smooth and unwrinkled surface.

A further object of the invention is to produce a device for effecting this which will be of simple form and which may be capable of adjustment widthwise of the web so that the wrinkles may be smoothed out at any particular point in the web at which they may occur.

With these and other objects not specifically referred to in view, the invention consists in certain novel parts, arrangements and combinations which will be fully described in connection with the accompanying drawings and the novel features thereof pointed out in the claims hereunto appended.

In these drawings—

Figure 1 is a side elevation of so much of a printing machine as is necessary for an understanding of the invention, the figure being partly broken away and partly in section;

Figure 2 is a side elevation, partly in section, of the improved smoothing device; and

Figure 3 is a detail plan view of part of 55 the construction shown in Figure 2.

Referring now to these drawings—

The invention has been illustrated as employed in connection with printing machines. It is understood, however, that it 60 may be used in other relations where it is desired to remove wrinkles from free running webs. The particular machine selected to illustrate the invention is a rotary intaglio press, one printing couple of which is shown 65 mounted in side frames 1, which are of any usual or suitable construction. This printing couple, in the particular construction illustrated, includes a form carrying cylinder 2 running in a fountain 3, a doctor 4 being 70 provided, as is usual in this class of machines for removing surplus ink. This form cylinder cooperates with an impression cylinder 5 mounted above the form cylinder in suitable bearings 7 carried from brackets 8 75 secured to the side frame 1. This impression cylinder is, as usual, adjustable by means of adjusting collars 9. The web is supplied from a suitable web roll, (not shown) this roll passing over tension roll 10 80 to and between the printing cylinders, over a guide roll 11 to and over a drying drum 12 and then over a guide roll 13 to be further operated upon in the machine, as perfecting. 85

In accordance with the invention, means are provided for smoothing out the wrinkles in the free running web, prior to the web passing between the printing couple, this smoothing device being preferably so arranged that 90 by a simple manipulation the wrinkles may be removed from the web at any point in its width. While the specific embodiment of these means may vary widely, in the particular construction illustrated there is provided a smoothing member over which the web is led with suitable tension, this smoothing member being marked 14, preferably of metal, and having an outer surface 15 polished so as to provide for free running of 100 the web. In the specific embodiment of the invention illustrated this member 14 is in the

form of a half round made so that its bearing surface, that is, the surface with which the web contacts, is adjustable widthwise of the web. In the particular construction illustrated this is effected by forming the half round of a light metal having sufficient flexibility so that its surface can be flexed toward or away from the web at any desired point widthwise thereof. While this may be effected in various ways, in the device shown, there is provided a support in the form of a rod or bar 16 carried in brackets 17 depending from the side frame 1, before referred to, this rod or bar being held in position in the brackets by set screws 18. This rod supports the half round which is secured at each end to the rod by bolts 19 having heads 20 and provided with lock nuts 21 on each side of the bar so as to firmly hold the half round in position. Intermediate the supporting bolts 19, the bar is drilled at a plurality of points to form passages in which work adjusting screws 22, these adjusting screws being provided with rounded heads 23 which bear against the inside of the half round, as clearly shown in Fig. 2, the other end of these screws being provided with grips 24 by which they may be easily and readily turned. With this construction, it will be seen that by adjusting the desired screw or screws 22, the half round may be flexed or bent outwardly, thus acting to spread the web as it passes over the round and remove any wrinkles that may be present therein, so that the web will go to the printing couple with a smooth surface. To permit this in and out movement of the half round, the latter is slotted at each end, as indicated at 25 in Fig. 3, the bolts 19 working in these slots. By providing the set screws across the round this action may be caused to take place at any point widthwise of the web where the wrinkles may appear and the adjustment is a very simple one to effect.

While the invention has been illustrated in its preferred form, it will be understood that various changes may be made in the form and arrangement of the smoothing de-

vice and that the invention is not limited to the specific form shown and described. 50

What is claimed is:

1. The combination with a printing couple to which a web is forwarded for printing, of a metal tensioning device having a smooth curved surface in contact with the web and over which the web runs, and means for independently adjusting the surface to and from the web at a plurality of points widthwise thereof. 55

2. A web smoothing device comprising a 60 metallic element extending widthwise of the web and having a smooth curved surface contacting with the web and over which the web runs, and means for independently adjusting the contact surface of the element 65 toward and from the web at different points widthwise thereof.

3. A web smoothing device having a 70 curved surface of flexible metal over which the web runs, and means for flexing the surface toward and from the web at a plurality of points widthwise thereof.

4. A web smoothing device comprising a 75 half round of flexible metal, a support therefor, and means for flexing the surface of the half round toward and from a web passing thereover.

5. A web smoothing device comprising a 80 curved surface of flexible metal extending widthwise of the web, and a plurality of adjusting screws arranged widthwise of the round for flexing the round toward and from the web. 85

6. A web smoothing device comprising a 90 curved surface of flexible metal extending widthwise of the web, a support, slots in the ends of the surface, connections working in the slots and securing the surface to the support, and a plurality of adjusting screws arranged widthwise of the surface beneath the 95 same for flexing the surface toward and from the web.

In testimony whereof, I have hereunto set my hand.

ERNEST G. BEVERIDGE.
